CLAIM

The ornamental design for a gaming machine, as shown and described.

DESCRIPTION

FIG. 1 is a front perspective view of a gaming machine showing our new design;

FIG. 2 is a front view thereof;

FIG. 3 is a left side view thereof;

FIG. 4 is a right side view thereof;

FIG. 5 is a cross-sectional view thereof taken through line 5-5 of FIG. 2;

FIG. 6 is a front perspective view of a gaming machine showing an alternate embodiment of our new design;

FIG. 7 is a front view thereof;

FIG. 8 is a left side view thereof;

FIG. 9 is a right side view thereof; and,

FIG. 10 is a cross-sectional view thereof taken through line 10-10 of FIG. 7.

The broken lines depicting the remainder of the gaming machine show features that form no part of the claimed design.

1 Claim, 10 Drawing Sheets
